UNITED STATES PATENT OFFICE

ADOLPH W. F. MANZEL, OF BUFFALO, NEW YORK, ASSIGNEE TO MANZEL BROS. CO., OF
BUFFALO, NEW YORK, A CORPORATION OF NEW YORK

OIL PUMP

Application filed February 5, 1927. Serial No. 166,125.

This invention relates to improvements in oil pumps, and while certain features thereof relate to multiple feed pumps, other features are adaptable for use in a single feed pump as well as in multiple feed pumps; and the invention particularly relates to that type of oil pump in which the oil is passed through a body or column of glycerine or other liquid material of greater specific gravity than the oil or otherwise possessing the qualities of allowing the oil to rise therein in globules.

One of the objects of my invention is the provision of an oil pump in which glycerine or a similar liquid substance is maintained within a sighting device having an oil outlet pipe connected thereto, and wherein said oil outlet pipe is readily detachable from the sighting device without detaching the latter from the pump casing, for the purpose of conveniently filling the sighting device with, or adding glycerine or the like to that within the sighting device.

Another object is to so construct an oil pump of the type referred to, in which the oil feeding devices are operated by actuating mechanism within the oil pump casing, so related to the oil feeding devices that the latter can be easily withdrawn from the pump casing without dismantling any portion of the actuating mechanism, or displacing such mechanism.

Another object is to provide, in an oil pump of the kind stated, oil feeding devices, each operatively connected with an oil-sighting device, and having both the oil feeding devices and the oil sighting devices supported by a wall of the pump casing and removable together from the casing.

Another object of my invention is the provision of an oil pump having an oil feeding device including a plunger, and actuating mechanism within the casing of the pump determining the range of movement of said plunger and thus predetermining the exact quantity of oil being fed by said oil-feeding device.

Another object of my invention is the provision of a pump in which a series of oil-feeding devices are arranged which are operated by actuating units operated mechanical-

ly in unison, or capable of being individually operated under manual effort, each actuating unit having means to separately regulate the amount of oil fed by its co-acting oil feeding device.

A further object of my invention is the provision of an oil pump having an oil-feeding device within its casing and having its outlet connected with a feed passage including a sighting device arranged outside of the oil casing so that any leak in said passage can be readily seen and assurance had that no portion of the oil delivered by said oil-feeding device will unknowingly be returned to the pump casing.

A further object is to provide an oil seal for the plunger of each oil-feeding device so that proper and effective action of the plunger is assured under all working conditions.

A further object is to provide an oil pump by means of which mechanically fed charges of oil will be delivered under pressure to various points to be lubricated and wherein the oil in its course of travel to such points will be visible.

A further object is to provide a pump in which a plurality of oil-feeding devices are used, each adapted to feed oil under pressure to certain parts of an engine or machine, and in which positive timing of the oil supply in relation to the movement of the engine or machine parts is assured.

Still further objects of my invention are to improve the construction of oil-feeding devices, and to improve on the actuating mechanism for said oil-feeding devices.

With the above and other objects in view to appear hereinafter, the invention consists in the novel features of construction and in the arrangement and combination of parts to be hereinafter described and more particularly pointed out in the subjoined claims.

In the drawings:

Fig. 10 is an enlarged horizontal section taken on line 10—10, Fig. 3, the casing being omitted.

Fig. 11 is a detached perspective view of the oil guide within one of the oil sighting devices.

Fig. 12 is a cross section through one of the rotatable actuators showing the same provided with three contact elements whereby the co-operating oil feeding device is actuated a corresponding number of times during each revolution of the actuator.

Fig. 13 is a similar view showing the actuator provided with two contact elements.

Fig. 14 is a detached perspective view of one of the rotatable actuators.

Fig. 15 is a detached perspective view of one of the rock levers forming part of an actuating unit.

Fig. 16 is a detached perspective view of the stop for limiting the plunger of the co-operating oil-feeding device.

Fig. 17 is a transverse section taken through a portion of line 3—3, Fig. 1, showing a different position of parts of one of the oil-feeding devices and the co-operating actuating unit.

Fig. 18 is a transverse section taken on the same plane as Fig. 3 and showing a modified construction of the connection of the oil outlet pipe to the sighting device, and a modified construction of the oil-feeding device.

Fig. 19 is a diagrammatic view showing the relative positions of the cam rollers as used with a four cylinder engine when timing the oil feed to the exact positions of the pistons in the engine cylinders, and in such cases the operating shaft may be square or octagonal.

Fig. 20 is a diagrammatic view showing the relative positions of the cam rollers as used with a six cylinder engine when timing the oil feed to the exact positions of the pistons in the engine cylinders, and in such cases the operating shaft may be hexagonal.

Reference being had to the drawings in detail, the numeral 20 designates the casing of the oil pump in which a supply of oil is contained, and while this casing may be of any desired formation or contour, it is preferably rectangular and constructed of sheet material. In the drawings it is shown as having a

bottom 21, side walls 22 and end walls 23, said bottom being secured in an oil-tight manner to said side and end walls. The side and end walls having inturned flanges 24 at their upper ends on which rests a gasket 25, and the upper end of the casing, which is otherwise open, is closed by a cover 26, which is firmly seated on said gasket and held in place along part of its marginal portions by screws 27 passed through the cover and gasket and threaded into the inturned flanges 24; also by fastening devices to be hereinafter described, and by means of which other parts of the pump are fastened in place.

The cover, or top wall of the casing, as it may be termed, is provided with a filler tube 28 through which oil is to be delivered into the casing, which oil is to be fed from the casing in predetermined small quantities by oil-feeding devices, to be hereinafter described. Oil may, however, be supplied to the casing in any other suitable manner.

Extending longitudinally through the casing or oil chamber, as it may be termed, is an operating shaft 29 which, in the main, is non-cylindrical in cross section. The shaft shown in the drawings is hexagonal along the greater portion of its length, and has cylindrical portions 30 at opposite ends which are journaled in bearings 31 secured to opposite end walls. These bearings are suitably packed to prevent leakage of oil along the shaft. Lengthwise movement of the shaft is prevented by reason of the fact that in turning the ends to cylindrical formation, shoulders 32 are formed which bear against the inner ends of the bearings 31.

Mounted on the non-cylindrical hexagonal portion of the operating shaft is a series of actuators 33, which are spaced at regular intervals along the shaft and each of which forms part of an actuating unit. Each actuator, in preferred form, comprises two disk-like members 34 connected together in spaced relation by a spacing pin 35 reduced at opposite ends to provide shoulders against which the disk-like members 34 bear, the ends of this pin being upset and serving as a rivet to hold the disk-like members in permanently spaced relation. On this spacing pin is rotatably mounted a contact element or member in the form of a cam-roller 36. By mounting the actuators on a non-cylindrical shaft, a positive drive is provided without the use of keys or key ways and this also allows the disk-like members carrying the cam-rollers to be positioned so that when the pump is used for lubricating a "Diesel" or other explosive engine, the order of the oil discharges will be in accordance with the firing order in the engine cylinders.

Arranged parallel with the operating shaft and extending through the casing or oil chamber is a fulcrum bar or spindle 37, the ends of which are stepped in bearings 38 secured in the end walls of the casing. These

bearings are liquid-tight so as to prevent leakage of oil at such points.

Spaced on said fulcrum bar or spindle 37 is a series of actuating or rock levers 39, one being provided for each actuator 33 and cooperating therewith. Each actuating or rock lever comprises two side members 40 which are constructed of sheet material, stamped into the desired shape, and held in spaced relation by a spacing pin 41 arranged at one end of said lever and a spacing member 42 arranged at the other end thereof. Like the spacing pins 35 of the actuators, the spacing pin 41 is reduced in diameter at its ends, 10 to form shoulders 43 which abut against the inner sides of the two side members 40, said reduced ends being upset to maintain said side members in permanently spaced relation. Mounted on the spacing pin 41 of each 20 actuating or rock lever 39 is a contact roller 44 adapted to actuate an oil-feeding device, in a manner to appear hereinafter.

The spacing member 42 of each actuating or rock lever 39 comprises rectangular spaced parts 45 having prongs 46 at opposite ends, which pass through openings 47 formed in the side members 40 of the actuating or rock lever, and these prongs are upset to fasten said spaced parts 45 to said side members and 25 maintain said members in permanently spaced relation.

Narrow separators 48 are placed between the spaced parts 45 and these also have prongs 49 extending through the openings 47 in the side members, one separator being arranged at each side of the actuating or rock lever 39, as clearly shown in Fig. 5.

The openings 47 in the side members of each actuating or rock lever are elongated transversely of said side members so that the prongs 49 of the separators and the prongs 46 of the spaced parts 45 forming the spacing member for said side members, are entered thereinto. The spaced parts 45 of said spacing member have registering openings 50 extending therethrough, which are screw threaded, and screwed into said openings is an adjustable contact member 51 which extends through the spacing member 42 and projects both above and beneath the same, as clearly shown in Figs. 3 and 17. The upper projecting portion of this adjustable contact member is provided with an axial socket or depression 52, and it also has at its upper end 40 an outstanding flange 53 which provides a bearing or contact surface for engagement with a rock arm or tappet 54 mounted on the fulcrum or spindle 37, guards against undue wear, and assures free and easy movement for said rock arm or tappet. The bore of said rock arm or tappet 54 is provided with a babbitt, brass, or other lining 55.

The rock arm or tappet 54 extends upwardly from the fulcrum bar or spindle 37 at 45 an inclination thereto and has an overhang-

ing portion 56 whose upper face is inclined, as at 57, to form a riding surface adapted to be engaged by the contact element or roller 36 of the actuator 44 to depress said rock arm or tappet during a predetermined portion of the rotary or oscillatory movement of said actuator, as the case may be; it being understood that said operating shaft may be given a continuous rotary motion, or a rocking or oscillatory movement, as may be desired. Said riding surface 57 extends from a point between the ends of said rock arm or tappet to the free outer end thereof and from the inner end of said riding surface 57 a second riding surface 57^a is provided which is at a greater inclination than said first-mentioned riding surface. In fact, the riding surface 57^a is a continuation of the riding surface 57. The cam-roller 56 of the actuator rides in contact with both riding surfaces and after passing over the angle formed by said surfaces causes a change in speed in the movement of the rock arm or tappet and consequently in the speed of the plunger of the oil-feeding device, to be hereinafter described. When the actuator shown in Fig. 3 is rotated clockwise, the cam-roller 56 of the actuator first engages the inclined riding surface 57 causing the rock arm or tappet 54 to be depressed at a certain speed and as the cam-roller rides over the angle or crest formed by the riding surfaces 57 and 57^a and rides in contact with the riding surface 57^a, the movement of the rock arm or tappet is increased. The under side of said overhanging portion 56 is rounded or made convex for contact with the contact surface at the upper end of the adjustable contact member 51. It will therefore be apparent that upon rotation or oscillation of the actuator 33, the contact roller 36 thereof will engage the inclined riding surfaces 57 and 57^a of the rock arm or tappet and cause the latter to swing downwardly on the fulcrum bar or spindle 37, with the result that through the medium of the adjustable contact member, which said rock arm or tappet engages, that end of the actuating or rock lever carrying said adjustable contact member is depressed, causing the opposite end of said lever to rise.

Each actuator 33, and the rock arm or tappet and actuating or rock lever associated therewith, form an actuating unit.

The adjustable contact member 51 has a stop pin 58 passed through its lower projecting end, the ends of said pin extending outwardly at diametrically opposite points so that when said contact member is adjusted upwardly in the spacing member 42 a certain distance, the extending ends of said pin will engage the under side of said spacing member; thus preventing accidental disconnection of the contact member from the spacing member.

An oil-feeding device 59 is provided for

each actuating or rock lever 39, and these oil-feeding devices are arranged in a series parallel with the operating shaft 29. Each oil-feeding device is suspended from the under side of an oil sighting device 60 having an extended base 61 large enough to cover an opening 62 formed in the top wall of the casing or oil chamber 20 and extending onto said top wall. Each oil-feeding device has a body or casing provided with a vertical bore 63 serving as a pump cylinder for an oil-forcing plunger 64 slidably disposed therein and extending downwardly beyond the lower end of said body or casing.

15 The upper end of the bore or cylinder 63 opens into a spring chamber 65 which in reality is a counterbored portion of said bore or cylinder and has its axis coincident with the axis of the latter. The exterior of said body or casing is reduced in diameter along its lower portion to provide a downwardly-facing shoulder 66 serving as a spring seat.

Near the lower end of the plunger a collar 67 is formed thereon and that portion of the 25 plunger beneath said collar, which may be termed the outer extremity of the plunger, is screw threaded, as at 68.

69 is a spring-retainer cup, the bottom of which is provided with an axial opening 30 through which the threaded extremity 68 of the plunger is passed, and screwed onto said threaded extremity is a nut 70 which forces the bottom of the cup against the collar 67 of said plunger and retains the same in 35 position on said plunger in a liquid-tight manner. The end of the plunger is preferably made flush with the nut so as to provide a smooth contact surface for the contact roller 44 of the actuating or rock lever co-operating 40 with said oil-feeding device. Surrounding the reduced lower portion of the body or casting of the oil-feeding device and extending a distance beneath the same so as to surround the projecting portion of the plunger is a 45 spiral spring 71, the lower end of which bears against the bottom of said spring retainer cup 69 and the upper end against the shoulder or spring seat 66 formed on the body or casting of said oil-feeding device, said spring serving 50 at all times to keep the plunger in lowered position and the lower end thereof in contact with the contact roller 44.

When supplying the pump casing with oil, it is filled to a level above the upper open end 55 of the spring retainer cup, with the result that the cup will be filled with oil. Owing to the fact that this cup is oil-tight it will remain filled with oil, even though the level of the oil within the pump casing is lower than the cup, 60 and it is to be noted that the oil in the cup at all times surrounds the lower end of the body or casing of the oil-feeding device so that, although the plunger 64 projects from the lower end of said casing, it cannot draw in air and 65 become inoperative for this reason.

The body or casting of each oil-feeding device has a lateral extension 72 provided with a circuitous oil passage 73, preferably of inverted V-shape, one leg of which has an inlet port 74 serving as an extension of said passage and arranged to open laterally into the bore or cylinder 63 of the oil-feeding device. This inlet port is in a plane beneath the bight 75 of said V-shaped oil passage, and the other leg thereof has connection with an oil inlet tube 76 extending downwardly therefrom to a point near the bottom of the casing or oil chamber 20. This oil inlet tube has oil inlets 77 at its lower end and is surrounded by a screen 78, or other filtering device, to filter the oil before entering said oil inlet tube.

In preferred form, the inlet leg of the inverted V-shaped oil passage 73 is enlarged at its lower end and internally screw-threaded, and the oil inlet tube 76 is secured into 85 said enlarged screw-threaded end, as at 79. The apex 80 of the wall between the legs of the inverted V-shaped oil inlet passage determines the height of the level of the oil within the cylinder 63, provided there is a constant flow of oil upwardly through the oil inlet tube 76, and the range of movement of the plunger upwardly beyond the highest point of said oil inlet port 74 determines the quantity of oil 90 being fed by said plunger.

An outlet port or passage 81 is provided for the cylinder 63, which has one end terminating near the upper end of the cylinder and its other end terminating at the bottom of the spring chamber 65. Said outlet port is normally closed by a valve 82; the valve in the preferred construction shown in Figs. 3 and 17 being cylindrical and entering the upper end of the cylinder 63 from the spring chamber 65, the extent of entrance into the cylinder 105 being sufficient to close the outlet port or passage 81. This valve has an annular flange 83 formed thereon which bears against the bottom wall of said spring chamber and governs the extent of entrance of the valve into the 110 cylinder.

A stop 84 is provided to limit the outward or downward movement of the plunger, this stop being formed of sheet material bent to provide two depending legs 85 and a stop member 86 connecting the lower ends of said legs and having an opening 87 therein through which the oil inlet tube 76 is passed. The legs 85 lie at opposite sides of the lateral extension 72 formed on the body or casting of the oil-feeding device and the stop member 86 is positioned in the path of the spring retainer cup 69, which may in a broad sense be considered as part of the plunger; so that broadly considered, the plunger may be said to engage this stop, which acts to limit the extreme downward movement of said plunger, in which position the plunger is in contact with the contact roller 44 on the actuating or rock lever.

Each oil sighting device 60 comprises a casting or casing 88 having a cylindrical portion provided with diametrically opposite sight openings 89. The extended base 61, heretofore referred to, is formed at the lower end of said casting or casing and is secured to the top wall at one side of the cylindrical portion by a screw 90, which is also passed through the top wall of the casing or oil chamber 20 at its marginal portion, through the gasket 25, and is threaded into the in-turned flange 24 directly beneath, and by means of a pair of screws 91 at the opposite side of said cylindrical portion; said screws 91 being passed through said extension and threaded into the cover of the casing or oil chamber.

Each oil sighting device closes the top of an oil-feeding device, and more particularly the top of the spring chamber 65 thereof and it has an annular depending flange 92 entering the upper end of said spring chamber, said flange surrounding a spring seat or socket 93 in which the upper end of a spring 94 within said spring chamber 65 is seated, the lower end of said spring surrounding the upper end of the valve 82 and bearing against the annular flange 83 thereof. In this manner the valve 82 is retained in normal position and assurance is had that unless subjected to high pressure from beneath, it will close the outlet port or passage 81.

Each oil-feeding device is provided with fastener flanges 95 at its upper end and is fastened to the under side of its co-operating sight feeding device by means of screws 96 passed through said fastener flanges, through a gasket 97 interposed between the two, and screwed into the base of the oil sighting device.

As there is a passage upwardly through the oil sighting device which is in direct connection with the spring chamber 65 at the upper end of the oil-feeding device and said spring chamber serves as a passage for oil upwardly therethrough, leakage of oil between the oil-feeding device and the oil sighting device is positively prevented.

The lower portion of the oil sighting device has an annular groove 98 formed therein, in which is placed an annular gasket 99 and against this gasket is seated the lower end of a glass sight tube 100. An oil passage 101 extends through the base of the oil sighting device and opens upwardly into the glass sight tube 100, the upper portion of said passage being enlarged to provide a valve seat 102. A nozzle 103 is screw-threaded into the enlarged upper portion of said oil passage 101 and extends upwardly into the sight tube 100. The lower portion of the passage through this nozzle is enlarged, as at 104, to form a downwardly-facing spring seat against which the upper end of a spring 105 bears, the lower end of said spring bearing

against a check valve 106, preferably spherical, which is seated against the valve seat 102 and closes the lower portion of the passage 101 from the oil-feeding device, thus preventing the glycerine or other liquid material used to fill the sighting device from draining into the oil-feeding device.

The upper end of the cylindrical casting or casing 88 is internally threaded, and by reason of the fact that this casting is provided with two diametral sight openings, it may be said to comprise an upper cylindrical portion and a lower cylindrical portion connected by concavo-convex oppositely-disposed members 107 having their edges spaced apart by the sight openings 89.

The upper end of the oil sight tube 100 extends into the upper cylindrical portion of the casting or casing 88 and has a gasket 108 resting against the upper edge thereof, a clamping and retainer nut 109 being threaded into said cylindrical upper portion and having a dependent annular flange 110 extending downwardly through the gasket and entering the oil sight tube, said clamping and retainer nut compressing the gasket and assuring an oil-tight joint at this point. Said nut 109 also serves to force the sight tube tightly against the gasket 99 so that an oil-tight joint is provided at the lower end of the tube.

For convenience in entering the clamping or retainer nut into and removing the same from the upper cylindrical portion of the casting or casing 88, said retainer nut, which is provided with an axial bore forming part of the oil passage through the sighting device, is also provided with diametrical tool slots or kerfs 111 for engagement by a suitable tool for rotating said nut.

A guide wire 112 is arranged centrally within the sighting device and extends downwardly from the upper end of the clamping and retainer nut 109 into the nozzle 103. This guide wire has a cross member 113 at its upper end provided at its extremities with downwardly bent terminals 114 which rest upon the upper surface of the clamping and retainer nut and hold the wire suspended axially within the oil passage extending through the sight tube and said nut. The lower end of said guide wire is crimped within the nozzle, as at 115. The oil forced above the check valve 106 accumulates at the crimped lower end of the wire and by capillary attraction is retained in contact with the wire while rising through the column of glycerine or other liquid substance, thus keeping it out of contact with the glass tube, which therefore remains clean and renders the movements of the oil globules upwardly through the tube visible at all times.

As already inferred, the oil sighting device is filled with glycerine or some other liquid substance of greater specific gravity than

of the oil to be fed, so that oil forced upwardly by the oil-feeding device will enter the oil sighting device and concentrate within or at the exit of the nozzle 103 so as to form into oil globules, which will rise upwardly along the guide wire 112 passing through the glycerine or other liquid substance within the sighting device.

The glycerine or other liquid substance extends upwardly into a connector 116 which serves to connect the oil sighting device with an oil outlet pipe 117. This connector comprises two members 118, 119, one of which is threaded into the upper end of the cylindrical casting or casing 88, and the other to the oil outlet pipe, by means of a suitable coupling 120. The two members of the connector are readily disconnectible so that access may be gained to the oil sighting device for supplying it with any deficiency in glycerine.

Member 118 of the connector is threaded into the upper end of the cylindrical casting or casing 88 and has an annular flange formed thereon between which and the upper edge of said casting or casing a gasket 121 is applied.

When this member 118 is threaded into position, the flange thereof compresses the gasket and renders the joint at this point liquid-tight. The upper end of this member is provided with a concaved seat 122 on which a gasket 123 is seated, and the member 119 has a bearing surface which is rounded or convexed to conform to said concaved seat and the gasket thereon. Member 119 also has an exterior shoulder against which a sleeve nut 124 is forced which is threaded onto the upper end of member 118.

In the passage through member 119 a valve seat 125 is provided, against which a valve 126, preferably spherical in formation, is seated; this valve being held against its seat by a spiral spring 127 bearing at one end against said valve and at its other end against a stop nut 128 having an axial opening therethrough.

The passages through the various parts of the oil sighting device, and those through the two parts of the connector may be said to form a continuous passage, of which part of it serves as a glycerine chamber. In the construction shown in Fig. 3, the glycerine may well extend up into the lower end of the passage formed through the member 118 of the connector so that the oil forced upwardly by the oil-feeding device occupies the space above the glycerine or other like substance, and at any rate fills the entire space within the connector member 119 above the valve therein and the oil outlet pipe 117 along the full length of the latter, regardless of the direction or distance it may extend.

It will be apparent, therefore, that after the outlet pipe is completely filled with oil

so as to displace all the air between the oil-feeding device and the point to be lubricated, the action and operation are as follows: At each stroke of the plunger 64, the oil trapped between the upper end of the plunger and the check valve 106 is forced upwardly to unseat said valve and assure a predetermined quantity of oil to pass the same. This causes the column of glycerine to be raised for a moment and act as a piston on the oil between it and valve 126, with the result that the exact quantity of oil is displaced from beneath valve 126 and passed beyond the same as is forced past the check valve 106. As the oil globules forming at the base of the glycerine column rise to the surface of the glycerine and mingle with the oil above it, the glycerine column lowers to its normal position.

Each of the actuating or rock levers 39 being fulcrumed between its ends may be said to embody two arms 130, 131, extending in opposite direction from the fulcrum bar or spindle 37 on which it is mounted, the arm 130 being the actuated arm or end of the lever, and the arm 131 the actuating arm or end of said lever. The actuating lever is adjusted so that when the plunger 64, or more particularly the spring retainer cup 69 of the plunger is in contact with the stop 84, the contact roller 44 carried by the arm 131 of the lever will be in contact with the plunger. This position determines the lowermost point of the range of movement of said arm; also the uppermost point of the range of movement of the arm 130 extending in the opposite direction from the fulcrum bar or spindle 37.

Upon adjusting the contact member 51 within the spacing member 42, in a manner to be hereinafter described, the extremity or free end of the rock arm or tappet 54 will be moved upwardly or downwardly, with the result that it will be engaged by the contact roller 36 at an earlier or later point in its circular path, and on account of the formation of said rock arm, said roller will permit said rock arm or tappet to rise after being depressed to its full extent. It will therefore be apparent that, upon adjusting said contact member 51 by unthreading the same within the spacing member 42, the rock arm will be raised and be under forcible action through a greater range of movement, with the result that the actuating lever 39 will oscillate through a longer arc of a circle and cause the plunger 64 of the oil-feeding device to move upwardly to a greater extent, thereby displacing a greater quantity of oil confined between the inner or upper end of said plunger and the valve 82. Lowering of the contact member within the spacing member 42 will result in the feeding of a lesser quantity of oil.

It is to be noted that the spiral spring 71

surrounding the reduced lower end of the body or casing of the oil-feeding device exerts its pressure downwardly and consequently in addition to normally maintaining the 5 plunger at the lowest point of its range of movement it also determines the normal position of the actuating or rock lever 38 and the parts carried thereby.

Generally, an oil pump of this type is designed for the purpose of feeding oil to various points and each of the series of oil-feeding devices has connection with an oil outlet pipe leading to one of said points. Each actuating unit therefore individually 10 controls an oil-feeding device, and as the oil supplied to one point to be lubricated may require more or less oil than another, and as movement of the actuating or rock lever of each actuating unit is separately controlled, 15 and the oil-feeding devices and the actuating mechanism comprising a plurality of units are confined within the casing or oil chamber 20, provision is made for individually adjusting the range of movement of each actuating 25 or rock lever from the exterior of the casing or chamber. For this purpose there is associated with each actuating unit a vertically movable and rotatably arranged rod 132, which is slotted at its lower end, as at 30 133, and has extending through the slot thereof, a pin 134 which is diametrically disposed in the contact member 51 so as to extend through the axial socket or depression 52 formed therein.

35 Fastened into the lower end of said rod 132, which may be termed a combined adjusting and manually actuating rod, and spanning the slot therein is a retainer pin 135, which serves to prevent disengagement of said rod from the pin 134; thus the rod has what may be termed flexible connection at its lower end with the adjustable contact member 51. This rod extends through a slot 136 formed in the overhanging portion 56 of the rock 40 45 arm 54. Said overhanging portion may therefore be said to be forked. For the purpose of guiding the rod 132 in its movement, a bracket 137 is provided within the oil chamber through which the rod is passed.

50 Mounted for rotary movement within the cover 26 of the casing is an adjusting sleeve 138, the projecting end of which is enlarged to form a head 139 which bears with its lower end against the upper surface of said cover. 55 In order to maintain said head in firm contact with the cover, a dished spring 140 is provided which surrounds the depending portion of said sleeve and bears with its outer edge against the under side of said cover with 60 its central portion against a collar 141 held in position on said sleeve by a spring retainer 142 entered in an annular groove formed in said sleeve. The combined adjusting and actuating rod 132 extends upwardly into the sleeve and it has a pin

143 passed therethrough with opposite ends projecting diametrically therefrom. The projecting ends of said pin are entered in longitudinal slots 144 formed in the wall of said sleeve at diametrically opposite 70 points; said pin and slot arrangement permitting rotation of said rod upon rotating said sleeve, yet allowing independent movement lengthwise of said rod, which is effected by a push pin 145 slidably arranged within the upper portion of said sleeve and extending upwardly beyond the upper end of the head thereof, said push pin having a head 146 providing a surface for convenient engagement by the hand. Said push pin has a stop shoulder 147 formed thereon against which engages retainer pins 148 arranged in the head of the adjusting sleeve 138, thus limiting the upward movement of said push pin. Said retainer pins are held in engagement with said shoulder by springs 149 which retain said pins in contact with said push pin during the movement of the latter. Due to the fact that the rod 132 is rotatable for adjusting the adjustable contact member 51 80 in its supporting actuating lever, it may, in addition to being termed a combined adjusting and manually actuating rod, be termed either an adjusting rod or an actuating rod, since upon rotation thereof it will adjust 85 the range of movement of its co-operating actuating or rock lever, and upon depressing the push pin 145, the latter will engage the upper end of said rod and cause movement of the actuating lever, which in turn will 90 actuate the plunger of the co-operating oil-feeding device without effecting its delivery or setting, or effecting the delivery or setting of the remaining oil-feeding devices.

95 For the purpose of rotating the combined adjusting and actuating rod 132, and through it the adjustable contact member 51, the adjusting sleeve 138 is rotated and the rotary movement thereof imparted to said rod through the pin and slot connection between 100 said rod and sleeve. However, when causing reciprocation of said rod, actuation of the adjusting sleeve is not necessary, as the push pin 145 is movable lengthwise within said adjusting sleeve.

110 When at any time it is found that mechanical actuation of the pump fails to supply the necessary or desired quantity of oil to any point and additional oil is desirable at such point, it is simply required to manipulate 115 the co-acting push pin 145 of the feeding device supplying such point, whereupon an additional quantity of oil is delivered to the point, during the mechanical operation of all the actuating parts, and in this manner 120 the co-acting actuating or rock lever may be manually operated several times during the interval between the mechanical operation thereof.

125 In order that the adjustable contact mem- 130

ber retains its adjusted position, a spring 150 is interposed between one of the side members 40 of the rock or actuating lever and the threaded peripheral face of the adjustable contact member, said spring being preferably formed as shown in Fig. 5 wherein it is illustrated as having a concaved portion 151 conforming to the curvature of the adjustable contact member and bearing thereagainst.

One or more of the actuators 33 of the series may be provided with a plurality of contact rollers 36; for instance as shown in Figs. 12 and 13, Fig. 12 showing three contact rollers embodied in the construction of the actuator, and Fig. 13, two. The number of contact rollers on an actuator may, of course, be varied, but it will be apparent that an actuator on the operating shaft 29 having a single contact roller will actuate its co-acting oil-feeding device once during each complete revolution of the actuator; whereas, another actuator on said shaft having two contact rollers will double the quantity of oil fed by its co-acting oil-feeding device, while a third, provided with three contact rollers, will triple the quantity, assuming adjustments of the co-acting actuating levers are alike.

Where the difference in quantity of oil fed by the oil-feeding devices during each reciprocating movement of their plungers, does not vary greatly, the variations for the same can be provided for by the adjustment of the adjustable contact members 51. Where, however, the supply is doubled or tripled, or otherwise changed in perceptible quantities, the difference in the quantities will be supplied by the number of times the actuating lever is operated by its actuator during each revolution thereof, and this depends on the number of contact rollers provided in the construction of such actuator.

The operating shaft may be rotated by a crank, shown for example at 152, Fig. 1, said crank being provided for manual operation; or, it may be operated mechanically by means of a pitman 153 secured to said shaft and having a connecting rod 154 pivotally connected to its outer end, also as shown in Fig. 1, or otherwise. The pitman may be caused to oscillate, in which case the actuators are given an oscillatory or rocking movement and oil is fed from the oil-feeding devices on both the clockwise and counter-clockwise movements of the actuators, or the pitman may be given a continuous circular movement, in which case the actuators will be caused to rotate. Ordinarily, a pump of this kind is mechanically operated, but when the operating shaft is being rotated, regardless of the means provided therefor, all of the actuating units are operated thereby, with the result that oil is fed by the oil-feeding devices through the vari-

ous oil outlet pipes 118, in predetermined quantities.

In the preferred construction I have shown the control valve 82 for the oil-feeding device of cylindrical formation and controlling a lateral outlet port or passage 81. In the modification shown in Fig. 18, the control valve, designated by the numeral 155, is spherical in formation and acts to close the upper end of the bore or cylinder 63. 75 This control valve 155 is arranged within a valve chamber 156 formed by counterboring the body or casting of the oil-feeding device at the upper end of the cylinder 63 to provide a shoulder 157, which serves as a valve seat for said valve, and the upper end of this counterbore is further enlarged to provide a second shoulder 158, also serving as a valve seat. In this modification, the valve preventing admission of glycerine into the oil-feeding device from the sighting device is disposed within the body or casting of the oil-feeding device at the upper end thereof, instead of in the oil sighting device, as in the preferred construction, and for this purpose a spherical check valve 159 is seated against the shoulder or valve seat 158, it being so normally maintained by a spiral spring 160 bearing at one end against said valve and at its other end against a shoulder 25 161 formed in the passage leading upwardly through the base of the oil sighting device. A spiral spring 162 is disposed between the two valves 155 and 159, bearing with opposite ends against said valves. In this modification, the oil is directed upwardly into the oil sighting device in a straight line, whereas in the preferred construction, the lateral oil port or passage 81 serves to direct the oil around the control valve 83 closing 105 the upper end of the bore or cylinder.

In said modification I have also illustrated a connector which will enable the ready disconnection of the oil outlet pipe 117 from the oil sighting devices so that any deficiency in 111 glycerine or other similar liquid substance being used within the oil sighting device may be conveniently supplied. In this particular construction the oil outlet pipe extends horizontally or laterally from the connection, instead of vertically or upwardly therefrom, as in the preferred construction. This modified form of connection comprises two members 163, 164 disposed one above the other with a gasket 165 interposed therebetween and fastened together by a bolt 166 having its shank 167 extending through the upper member and screw-threaded into the lower member 164. This shank has a longitudinal passage 168 opening into the enlarged passage formed in 120 said member 164 at the bottom thereof, and a transverse passage 169 intersecting said longitudinal passage. The upper member 163 has a lateral extension 170 to which the oil outlet pipe 117 is connected, and through this lat- 130

eral extension a passage 171 is formed which is in registration with the transverse passage 169 formed in the sleeve extension of the nut 166. In the passage 171, a valve 172 is arranged which is controlled by a spring 173 acting in a manner similar to the valve and spring shown in the upper member of the connector illustrated in the preferred construction. In order to replenish any deficiency in the glycerine within the sighting device, it is simply necessary to remove the bolt 166, after which the two members of the connector may be separated and the glycerine poured into the lower member to the desired level.

The operation of the pump, as thus far defined, is as follows:

Oil is supplied to the casing or oil chamber 20 through the filler tube 28, or otherwise 20 to a level above the top of the spring-retainer cup 69 so that the latter will be completely filled with oil. The oil thus furnished to the chamber is drawn upwardly through the oil inlet tubes 76 during the actuation of the 25 pump, this being effected by an operating part of the machine to which the pump is applied, or by any separate power medium, for the purpose of rotating the operating shaft 29. This shaft causes rotation of the several 30 actuators 33 thereon and through the medium of one or more contact rollers 36 on each actuator, depresses the rock arms or tappets 54. The downward movement of these rock arms or tappets cause the actuating or rock 35 levers 39 to be operated through the medium of the adjustable contact members 51 carried thereby; that end of each actuating lever having the adjustable contact member moving downwardly, while the opposite end having 40 the contact roller 44, moves upwardly. By reason of the connection of the combined adjusting and actuating rods 132 to the adjustable contact members 51, said rods are caused to move downwardly with the actuating levers, such movements being permitted by the 45 pins 143 at the upper end of the rods traveling in the slots 144 formed in the adjusting sleeves 138, without in any manner effecting said sleeves.

The movement of the actuating or rock levers 39, by reason of the contact rollers 44 thereof being in engagement with the plungers 64 of the several oil devices, causes said plungers to move upwardly, and as the projecting ends of these plungers are oil-sealed within the spring-retainer cups, admission of air to the cylinders is impossible and effective operation of the oil-feeding devices is assured at all times. The oil within the bores or cylinders 63 of the oil-feeding devices, between the plungers and the valves 82 in said bores or cylinders, is acted upon by the plungers, and as the upper ends of the plungers are normally beneath the highest points of the respective oil inlet ports

74, each of the plungers has an initial ineffective stroke-portion which becomes completed when the plunger reaches a point to fully close its inlet port. The remaining portion of the stroke of each plunger, which is the effective portion thereof, causes the body of oil between the plunger and the control valve 84 to lift said valve and uncover the outlet port or passage 81, at the same time forcing a quantity of oil, predetermined by the range of the effective stroke of the plunger, outwardly through said port or passage, around the control valve, through the spring acting against said valve and the chamber in which said spring is located, and into the oil sighting device; the pressure exerted being sufficient to lift the check valve 106 and allow the oil to travel upwardly to the bottom of the glycerine column and rise in globules through the body of glycerine contained within the oil sighting device. The glycerine is held against flowing into the oil feeding device by the check valve 106 in each oil sighting device, or its equivalent in the modified construction shown in Fig. 18. The oil passing upwardly through the nozzle is broken up by the crimped lower end of the guide wire 112 extending through the sight tube 100 and is formed into globules rising upwardly through the body of glycerine so that the exact quantity being delivered with each actuation of an oil-feeding device can be easily seen. This oil accumulates on top of the body of glycerine in the oil sighting device and fills any space that may exist between the level of the glycerine and the valve 126 in the connector, so that the exact quantity of oil passing upward in globular form through the oil sighting tube 100 is exactly that passing the valve 126 is the connector. As the entire oil outlet pipe is filled with oil, the pressure created by the plunger of the oil-feeding device will cause delivery, at the point to be oiled, of exactly that quantity forced from the cylinder 63 during each upward stroke of the plunger 54.

The downward movement of the plunger 64 of each oil-feeding device and the movable parts comprising the actuating unit co-operating therewith and the combined adjusting and manually actuating rod 132 connected to the adjustable contact member 51 of said unit, are returned to normal position by the spiral spring 71 surrounding the lower reduced portion of the oil-feeding device.

In Fig. 1 I have shown five oil sighting devices and consequently the casing or oil chamber 20 contains five actuating units, with each of which there is associated a combined adjusting and manually actuating rod 132. If, for example, it is found that the oil fed to the point to be lubricated by the parts associated with the central oil sighting tube in Fig. 1, is insufficient for proper lubrication, the push pin 145 associated with the combined

adjusting and actuating rod 132 connected to the actuating unit of said oil sighting tube is raised and lowered manually a number of times, which may be effected during mechanical operation of the pump units, and this will cause additional quantities of oil to rise upwardly through the central oil sighting device, in addition to that passing therethrough during the mechanical operation of the parts associated therewith. Should it be found, upon examination of the sight tubes, that a slight increase of oil would be desirable at any point, it would be simply necessary to rotate the associated adjusting sleeve 139, whereupon the combined adjusting and actuating rod 132 associated therewith would be rotated and cause the adjustable contact member 51 of the co-acting actuating or rock lever to be elevated within the spacing member 42 of said lever, with the result that both the associated rock arm or tappet and actuating or rock lever would be compelled to travel through a somewhat longer range of movement, and this would increase the effective stroke of the plunger associated therewith and deliver an increased quantity of oil from the feeding device.

By applying the oil sighting devices directly above the oil-feeding devices the transverse dimension of the pump is considerably reduced while the slight additional height is of no consequence owing to the fact that pumps of this type are invariably mounted vertically, and as the projecting ends of the oil-forcing plungers are at all times oil-submerged, even though the level of the oil in the pump casing is considerably below the oil-feeding devices, all advantages possessed by the types of pumps having the oil sighting devices at the side of the casing are retained herein supplemented by the additional advantages herein set out.

In some cases, especially when applying pumps to "Diesel" engines, the exact time of delivery of oil to the point to be lubricated is of decided advantage. For example, it is highly desirable, in engines of the Diesel type to deliver oil in proper quantities to the engine pistons, and particularly when the pistons are at certain points in their range of movement. As shown in the diagrammatic views, Figs. 19 and 20, each of the engine cylinders, designated by the numeral 174, has an oil hole 175 opening to the interior thereof at a certain point between its ends over which the piston 176 within the cylinder passes, so as to cover and uncover the same, and the oil outlet pipes 117 lead to these oil holes. It is desirable that the feeding of oil be timed so that upon delivery, the pistons will be at the end of the working stroke, and by proper delivery, the efficiency of the engine will be greatly increased and cost of lubrication reduced. When timing the oil supply to the stroke of the pistons, the pump is, of course,

operated in synchronism with the engine and the actuators 34 are positioned rotatively on the operating shaft 29 to harmonize with the arrangement of the engine pistons; this being clearly shown in Figs. 19 and 20.

Having thus described my invention, what I claim is:—

1. In an oil pump, the combination of a pump cylinder having a lateral extension provided with an inverted V-shaped oil passage, the lower end of one leg of which is connected with the interior of said cylinder by a lateral oil inlet, said cylinder having a lateral oil outlet spaced from said oil inlet, a spring-retained valve fitting into the upper end of said cylinder and having its lower end in a plane beneath that of the apex of said inverted V-shaped oil passage, said valve normally closing said oil outlet, a plunger extending into said cylinder from the lower end thereof and having its upper end separated from said valve by an intervening oil space normally in communication with said oil inlet, and means for imparting movement to said plunger to cause said valve to open said oil outlet through the force supplied by said plunger on the intervening body of oil and to force a predetermined quantity of said oil out of said outlet.

2. In an oil pump, a pump cylinder having a lateral extension provided with a circuitous oil passage having its inlet and its outlet at low points and having said passage outlet serving as an oil inlet for said cylinder, said circuitous passage having an intermediate portion at a high point compared to its inlet and outlet, said cylinder having an oil outlet in a plane above that of its oil inlet, a valve normally closing said oil outlet and movable through a predetermined portion of its range of movement before opening said outlet, a plunger within said cylinder separated from said valve by a space into which said oil inlet opens and which is filled with oil, the highest point of said space being in a plane beneath the highest point of said oil passage, said plunger being adapted to open said valve through the interposed body of oil within said space, and means for imparting movement to said plunger.

3. An oil pump having a pump cylinder provided with a plunger bore and a spring chamber at one end thereof co-axial with said bore, said plunger bore having an oil inlet and an oil outlet spaced from said oil inlet along the length of said bore, an oil passage connecting said oil outlet with said spring chamber, a plunger reciprocable within said bore and having its inner end normally positioned to uncover said oil inlet, a valve in said plunger bore closing said oil outlet and having a portion extending into said spring chamber, said valve being provided with an annular flange normally bearing against the inner end wall of said cham-

ber, a closure applied to the upper end of said pump cylinder and having an outlet passage therein, and a spring surrounding a portion of said valve and bearing at one end against 5 said closure and at its other end against the annular flange of said valve.

4. In an oil pump, the combination with an oil-containing casing having a top wall closing the same, of a plurality of oil-feeding devices within said casing, actuating mechanism also within said casing for actuating said oil-feeding devices including a vertically-movable rotatably-adjustable rod for each of said oil-feeding devices, a sleeve 10 co-acting with each of said rods and rotatably mounted in said top wall, each sleeve having the upper end of one of said rods extending therewith and being provided with co-acting guide means to permit independent 15 vertical movement of said rod but to prevent independent rotary movement thereof, said sleeve being provided with a collar spaced from the under side of said top wall, a dished spring resting upon said collar and exerting 20 pressure against the under side of said top wall to retain said sleeve in position within said top wall, and a manually-operable plunger rod within said sleeve adapted to engage the upper end of said rod and cause independent 25 operation of the individual oil-feeding device co-operating with said rod.

5. In an oil pump, the combination with an oil-containing casing, of an oil-feeding device within said casing, a rotatable shaft arranged within said casing and operated from the exterior thereof, an actuator on said shaft comprising two spaced disks and a contact device connecting said disks off-center, and means interposed between said actuator 30 and said oil-feeding device engaged by the contact device of said actuator and adapted to cause actuation of said oil-feeding device.

6. In an oil pump, the combination with an oil-containing casing, of an oil-feeding device within said casing, a rotatable shaft arranged within said casing and operated from the exterior thereof, an actuator on said shaft comprising two spaced disks, a pin connecting said disks off-center and retaining 45 the same in spaced relation and a contact roller rotatable on said pin, and means interposed between said actuator and said oil-feeding device engaged by said contact roller and adapted to cause actuation of said oil-feeding device.

7. In an oil pump, the combination with an oil-containing casing, of an oil-feeding device within said casing, a rotatable shaft arranged within said casing and operated from the exterior thereof, an actuator on said shaft comprising two spaced disks, pins connecting said disks off-center and holding said disks in spaced relation and a contact roller rotatable on each of said pins, and means 55 interposed between said actuator and said oil-

feeding device engaged by said contact rollers and adapted to cause actuation of said oil-feeding device a plurality of times during each revolution of said actuator.

8. In an oil pump, the combination with a casing, of an oil-feeding device within said casing, a rotatable shaft arranged within said casing and operated from the exterior thereof, an actuator on said shaft comprising two spaced disks, pins connecting said disks at regulator intervals around said pins between said disks, and means interposed between said actuator and said oil-feeding device engaged by said contact rollers and adapted to cause actuation of said oil-feeding device.

9. In an oil pump, an oil-containing casing, an oil-feeding device within said casing, a non-circular shaft arranged within said casing and operated from the exterior thereof, an actuator on said shaft comprising two spaced disks having non-circular openings conforming to the shape of said shaft and being forced onto and retained in spaced relation on said shaft, a pin connecting said disks off-center and assisting in maintaining the same in spaced relation, a contact roller rotatable on said pin, and means interposed between said actuator and said oil-feeding device engaged by said contact roller and adapted to cause actuation of said oil-feeding device.

10. An oil pump, comprising an oil-containing casing, an oil-feeding device within said casing including a plunger, a shaft rotatable within said casing and operated from the exterior thereof, a non-rotatable shaft parallel with said rotatable shaft and spaced therefrom, a rock lever mounted between its ends on said non-rotatable shaft to provide opposite projecting arms, an actuator on said rotatable shaft and adapted to impart force to one of said arms for rocking said lever, and a contact roller applied to the other of said arms and engaging the plunger of said oil-feeding device for actuating the same.

11. An oil pump, comprising an oil-containing casing, an oil-feeding device within said casing, a rotatable actuator, a non-rotatable shaft, a rock arm mounted on said shaft and adapted to be engaged by said actuator, a rock lever also mounted on said shaft and actuated by said rock arm, said rock lever engaging said oil-feeding device to actuate the same and having an adjustable contact member in engagement with said rock arm.

12. An oil pump, comprising an oil-containing casing, an oil-feeding device within said casing including a plunger, a rock lever mounted between its ends for rocking movement and comprising two side members spaced apart, a spacing element connecting said side members together at one end of said rock lever and provided with a screw threaded opening, the other ends of said rock lever

- being in contact with said plunger, a contact member adjustably threaded into the threaded opening of said spacing element and having a socket at its upper end, a pin extending diametrically through said socket, a vertically movable rod having a forked end through the slot of which said pin is passed, a pin extending through the forked end of said rod underneath and at right angles to said first-
5 mentioned pin to prevent withdrawal of said rod from said socket, a rock arm having its axis coincident with the axis of said rock lever and having its free end forked to straddle said rod, said rock arm being provided
10 with a convex contact portion engaging the upper end of said contact member at opposite sides of said rod, a rotatable actuator adapted to engage said rock arm for actuating the same and cause actuation of said rock
15 lever, and manually-actuated means extending partly outside of said casing and adapted to engage the upper end of said rod for actuating the same and the rock lever independent of said rock arm.
20 13. An oil pump, comprising an oil-containing casing, an oil-feeding device within said casing including a cylinder and a piston plunger projecting from the lower end of said cylinder, a cup secured to the lower end
25 of said piston plunger in an oil-tight manner and having its upper edge at all times in planes above the lower end of said cylinder, said cup containing a sealing fluid, and means for operating said plunger.
30 14. An oil pump, comprising an oil-containing casing, a plurality of oil-feeding devices, an actuating unit for each of said oil-feeding devices, means for adjusting the movement of said actuating units to cause
35 feeding of like or varying quantities of oil by said oil-feeding devices, mechanical means for actuation of said actuating units, and means for manually and individually operating any of said actuating units and cause
40 a co-operating oil-feeding device to feed the maximum charge of oil regardless of the adjustment of said actuating unit.
45

In testimony whereof I affix my signature.
ADOLPH W. F. MANZEL.
